UNITED STATES PATENT OFFICE.

ISAAC H. VOORHIES, OF YPSILANTI, MICHIGAN.

IMPROVEMENT IN CAR-BRAKES.

Specification forming part of Letters Patent No. 137,264, dated March 25, 1873.

To all whom it may concern:

Be it known that I, ISAAC H. VOORHIES, of Ypsilanti, in the county of Washtenaw and State of Michigan, have invented certain new and useful Improvements in Car-Brakes; and I do hereby declare that the following is a full, clear, and exact description thereof, reference being had to the accompanying drawing and to the letters of reference marked thereon which form a part of this specification.

The nature of my invention consists in the construction and arrangement of devices for operating a car-brake, which acts on the axle of the car, and is so arranged that it can be operated by the engineer for the whole train or by one man or boy on a single car, the power being taken from the axle of the engine or of each car.

In order to enable others skilled in the art to which my invention appertains to make and use the same I will now proceed to describe its construction and operation, referring to the annexed drawing, in which—

Figure 1 is a plan view, and Fig. 2 a longitudinal section, of my invention. Fig. 3 shows a section of the chain used. Fig. 4 shows a shaft with spring and cylinder.

A represent the ordinary brakes now generally in use, and B the brake-lever operating the same through the usual rods *a a*, connected with the brake-bars *c c*. Power is applied to the brakes by passing a chain, *b*, from the brake-lever *B* down the axle *D* of the car, and once or twice or half around the axle, as may be found most desirable, and then up to a grooved pulley, *E*. Thence to the center of the car and fastens to a shaft, *G*, which is placed directly across the center of the car and under the body of the same. This shaft *G* has two grooved wheels, *H H*, one at each end, and a cord, rope, round leather belt, or chain, *d*, is passed once or twice around one of said grooved wheels. The back end of the cord *d* is to be fastened to a spring, *x*, made of wire or any other suitable material, one end of which spring is fastened to a shaft, *y*, and a cylinder, *z*, put over on the outside of said shaft and spring, with the other end of the spring attached to the cylinder. The other end of the cord *d* is then passed forward to

the next car and then twice around a similar grooved wheel, *H*, at the center of this car, then to the next car, and so on through the whole train to the axle *I* of the engine, or of the tender, as may be most convenient for operation. In passing the cord around the drive-axle *I* it may be necessary to pass it first over a pulley directly above the axle, and then down to the axle and half or once around, and then up to the cab or back to a wheel, *e*, on the bottom of the brake-wheel or rod *J* now in use.

By turning the brake-wheel and rod *J*, the chain or cord *d* becomes sufficiently tightened to cause the drive-axle *I* to turn the shaft *G*, which in turn, through the chain *b*, acts on the brake-lever *B* to apply the brakes, and the spring *x* yields to prevent breakage, and when the brakes are let off winds up the cord. The chains when they wear on the axle are made, as shown in Fig. 3, with flat links *ff* riveted together, and wear-irons *h h* dovetailed in across each link. The shaft *G* has a wheel, *H*, at each end, so as to pass the cord *d* on either side in case of changing ends with the car.

Having thus fully described my invention, what I claim as new, and desire to secure by Letters Patent, is—

1. The arrangement, substantially as herein described, of the chain *b*, pulley *E*, and center shaft *G*, for operating the brake-lever, as herein set forth.

2. The arrangement of the drive-axle *I*, cord *d*, pulley *e* on the brake-wheel, and rod *J*, and the pulley *H* on the center-shaft *G* for turning said shaft, substantially as shown and described.

3. The wear-irons *h h* dovetailed into the links *ff* of the chain where said chain passes around the axle, substantially as herein set forth.

In testimony that I claim the foregoing as my own I affix my signature in presence of two witnesses.

ISAAC H. VOORHIES.
